HANDLE FOR DISHES.

No. 15,628.

Patented Dec. 16, 1884.

UNITED STATES PATENT OFFICE.

CHARLES EDWARD HAVILAND, OF LIMOGES, FRANCE.

DESIGN FOR A HANDLE FOR DISHES.

SPECIFICATION forming part of Design No. 15,628, dated December 16, 1884.

Application filed November 18, 1884. Term of patent 14 years.

To all whom it may concern:

Be it known that I, CHARLES EDWARD HAVILAND, a citizen of the United States, residing at Limoges, Republic of France, have 5 invented and produced a new and original Design for Handles of Dishes, fully described and represented in the following specification and the accompanying drawings, forming a part of the same.

10 In said drawings the perspective views of the dishes shown represent by Figure 1 a jug or pitcher; by Fig. 2, a sugar-bowl; by Fig. 3, a tea-pot, and by Figs. 4 and 5 covered dishes.

15 The design embraced herein, and which relates to the dishes of a table-service which require or may have handles applied to them, consists in the configuration of the handle, which is found in the representation of a 20 stalk having blade-like leaves and heads of wheat projecting therefrom.

No description is herein given of the body ornamentation, or of what is technically known as the "decoration," for the reason that the 25 former is embodied in a companion application, No. 136,778, filed July 3, 1884, and the latter forms no part of the design, and for the further reason that either or both may be varied, as fancy may dictate or trade requirements demand, without affecting the design 30 constituting the subject-matter hereof.

The configuration of the bodies of the dishes shown in Figs. 1, 2, 3 forms no part of my invention.

35 The design for the handles, whether constituting a side handle, as in Figs. 1, 3, 5, and 6, or of

a top handle, as in Figs. 2, 3, 5, and 6, and whether placed horizontally or vertically, or at any angle of relation to the body of the dish or its cover, is composed of a stalk, 5, curved 40 so that its opposite ends rest upon the surface of the dish body or cover, and said stalk supports one or more heads of wheat, 6, represented as growing from it, and has projecting leaves, as 7, of which there may be any number. The stalk is curved somewhat like the letter S, when viewed from above, as in the cases of its application to the covers, (see Figs. 2, 3, 5, and 6;) but the stalk may be more or less straight, as is represented in the vertical 45 handles shown in Figs. 1 and 3, and in the horizontally-arranged handles shown in Figs. 2, 5, and 6.

While in most cases it is preferable that the handles shall not be colored or otherwise ornamented, its several elements may, singly or wholly, be beautified by coloring, and any decoration supplemental to the handle may be added without affecting the design.

55 What is claimed is—

The design for the handles of dishes, the same consisting in the stalk 5, having leaves 7 and heads of wheat 6, as shown and described.

In testimony whereof I have hereunto set 65 my hand in the presence of two subscribing witnesses.

CH. ED. HAVILAND.
